LET-OFF FOR LOOMS.

1,124,465.

Specification of Letters Patent.

Patented Jan. 12, 1915.

Application filed August 18, 1909. Serial No. 513,495.

To all whom it may concern:

Be it known that I, LOUIS H. LANDRY, a citizen of the United States, residing at Uxbridge, in the county of Worcester, and 5 State of Massachusetts, have invented a new and useful Let-Off for Looms, of which the following is a specification.

This invention relates to a friction let-off for looms.

10 The principal objects of the invention are to do away with the weights ordinarily employed for this purpose; to provide a construction which can be made in a small compact way so that very little space will 15 be taken up; and to provide for certain adjustments and for an adjustable yielding connection between the several elements of the mechanism; also to provide a construction in which the reduction in size of the 20 warp beam will tend to let-off the tension, while if desired, the operator can readily operate part of the mechanism by hand for the purpose of increasing the tension.

25 Further objects and advantages of the invention will appear hereinafter.

Reference is to be had to the accompanying drawing in which the figure is an end elevation of one embodiment of the let-off motion showing enough parts of the warp 30 beam to show how the invention is applied thereto.

The drawing shows a part of the warp 10 on a warp beam which has a stud 11 and friction disk 12. On this friction disk is 35 mounted a friction band 13 connected at one end with a stud 14 fixed on the end of the loom frame and having a free end 15 to which is pivotally connected a link 16 which is screw-threaded and has nuts 17 for holding in adjusted position a spur 18. This 40 spur is adapted to fit in any one of a plurality of notches 19 on the short arm of a lever 20 which is pivoted on the frame. This lever preferably is located directly 45 above the friction disk so that the short arm is substantially at right angles to the direction of the link 16 which is tangent to the circumference of the friction disk, and the long arm extends almost in a horizontal direction, but slightly inclined, over the friction 50 disk. This long arm has a notch 21 into which one end of a lever 22 projects. The other end of this lever extends into a notch 23 on a third lever 24. The lever 24

has a notch 25 at the other end for receiving a spur 26. This spur is provided with a flange 27 and is perforated so that a rod 28 can pass freely through it. This rod also passes through a notch or slot in the end of the lever 24. On this rod above the movable flange 27 is a fixed flange 29 and a spring 30 is located between these flanges so as normally to force the flange 27 downwardly. The rod is provided with a screw-thread 31 and with an operating hand wheel 32. On the screw-thread is an adjustable nut 33 having a notch 34 for receiving the end of a fourth lever 35. The opposite end of this lever engages in a notch 36 on the short arm 37 of a hand-operating lever 38. The main portion of this lever 38 extends through the pivot thereof from a handle 39 to a roller 40 which bears on the warp. The short arm 27 extends from a point near the pivot in an angular direction. Each of these levers 20, 22, 24, 35 and 38 is shown as of that class of levers which have their fulcrum between the two points at, and to which, the force is applied, but it will be understood that other forms of levers or other mechanism can be substituted therefor. With the form shown, or any other form embodying the same principles, the mechanism can be located in a very small space and in a convenient location on the frame of the loom which supports the several pivots of the levers.

The operation is as follows:—The tension on the band 13 is applied through the lever- 90 age by the bearing of the warp on the roll 40 and when the warp beam decreases in size the roll 40 tends to move to the left in the figure which tends to bring the end of the short arm 37 down, which allows the spring 95 28 to force the upper arm of the lever 35 up. This release of tension of the spring will allow the left end of the lever 24 to move up, which allows the upper arm of the lever 22 to move down and the long arm of the lever 100 20 to move up. This permits the short arm of the lever 20 to move to the right which obviously lessens the tension on the friction band. On the other hand, while the operator cannot use the handle 37 to reduce the 105 tension, he can swing it to the left so as to swing the roll 40 away from the warp beam which will force the spring 28 down and

perform the opposite function to that just described, so as to increase the tension on the friction disk. In case of emergency, however, the operator can turn the hand wheel 32 in either direction to increase or decrease the friction.

It will be obvious that various adjustments can be secured by means of the nuts 17 or by turning the hand wheel 32, thus practically adjusting the position of the nut 33.

While I have illustrated and described a preferred embodiment of the invention, I am aware that many modifications can be made therein by any person skilled in the art without departing from the scope of the invention as expressed in the claims. Therefore, I do not wish to be limited to all the details of construction shown and described, but

20 What I do claim is:—

1. In a device of the character described, the combination with a warp beam and a friction let-off therefor, of a lever adapted to bear on the warp on the warp beam, said lever having a short arm fixed thereto, an adjustable yielding connection, means connected with the short arm for applying pressure longitudinally to one end of said yielding connection, and means for connecting the other end of said yielding connection with the friction let-off to apply the pressure therefrom to the friction let-off and increase the tension on the warp beam.

2. In a device of the character described, the combination with a warp beam and a friction let-off therefor, of a lever pivoted near its center connected with the friction let-off, said lever having a notch, a rod located at an angle to said lever, a flange freely movable on said rod, said flange having a spur engaging in the notch on said lever, said rod having a second flange fixed thereto and a screw-thread, a spring between said flanges, a nut on the screw-thread having a notch, a lever engaging in the notch on the nut, and means whereby the variations in the size of the outside diameters of the body of warp on the warp beam will cause the last named lever to move so as to tend to compress said spring.

3. In a device of the character described, the combination of a warp beam having a friction disk connected therewith, a friction band on the disk, a lever having a long arm and a short arm, said short arm being located near the free end of said friction band and having a plurality of notches therein, a link on the free end of the friction band having a projection adapted to engage in one of said notches, a spring connected with the long arm of said lever, and a system of leverage connected with the spring and adapted to engage the warp of the warp beam for letting off the friction as the warp beam decreases in size.

4. In a device of the character described, the combination with a warp beam having a friction disk thereon, of a friction band on the disk, a lever located over the friction disk, said lever being connected with the loose end of the friction band, a lever pivoted above the first named lever and engaging it, a third lever adapted to be engaged at one end by the second lever, a resilient member connected with the other end of the third lever, a fourth lever having one end engaging the resilient member, and an operating lever adapted to bear on the warp on the warp beam and connected with the other end of said fourth lever.

5. In a device of the character described, the combination with a warp beam and a friction let-off therefor, of a lever pivoted near its center, a system of leverage connected with one end of said lever and with the friction let-off, the other end of said lever having a notch, a rod located at an angle to said lever, a hollow flange freely movable on said rod and through which the rod projects, said flange having a spur engaging in the notch on said lever, said rod having a second flange fixed thereto and a screw-thread, a spring between said flanges, a nut on the screw-thread having a notch, a lever engaging in the notch on the nut, and means whereby the variations in the size of the outside diameters of the body of warp on the warp beam will cause the last named lever to move so as to tend to compress said spring.

6. In a device of the character described, the combination with a warp beam and a friction let-off therefor, of a system of leverage connected with said friction let-off, a reciprocable rod, a hollow flange freely movable on said rod and through which the rod projects, said flange having a spur connected with said leverage system, said rod having a second flange fixed thereto and a screw-thread beyond it, a spring between said flanges, a nut on the screw-thread having a notch, a lever engaging in the notch on the nut, a hand lever having a roll adapted to bear on the warp on the warp beam and having a handle by which the lever may be moved to swing the roll away from the warp beam, said lever having a short arm projecting therefrom between the handle and roll and connected with the last named lever, whereby motion of the hand lever in one direction will increase the tension on the warp beam and in the other direction will decrease it.

7. In a device of the character described, the combination with a warp beam and a friction let-off therefor, of a system of leverage connected with said friction let-off, a hand lever having a roll adapted to bear on the warp on the warp beam and having a handle by which the lever may be moved

- to swing the roll away from the warp beam, said lever having a short arm projecting therefrom between the handle and roll and connected with the friction let-off, whereby motion of the hand lever in one direction will increase the tension on the warp beam and in the other direction will decrease it.
8. In a device of the character described, the combination with a warp beam having a friction disk thereon, of a friction band on the disk, a lever having two arms located over the friction disk, one of said arms being connected with the loose end of the friction band, an operating lever adapted to bear on the warp on the warp beam, a system of levers connected with the other arm of the first named lever and with said operating lever for transmitting motion from one to the other, a spring between two of the levers of said system, and means for adjusting said spring.
9. In a device of the character described, the combination with a warp beam and a friction let-off therefor, of a reciprocable
- rod, a hollow flange freely movable on said rod and through which the rod projects, said flange having a spur connected with said friction let-off, said rod having a second flange fixed thereto and a screw-thread beyond it, a spring between said flanges, a nut on the screw-thread having a notch, a lever engaging in the notch on the nut, a lever having a roll adapted to bear on the warp on the warp beam having an arm projecting therefrom between the handle and roll and connected with the last named lever, whereby motion of the hand lever in one direction will increase the tension on the warp beam and in the other direction will decrease it.

In testimony whereof I have hereunto set my hand, in the presence of two subscribing witnesses.
